UNITED STATES PATENT OFFICE.

CHARLES H. FORT, OF STAFFORD, KANSAS.

MEASURING DEVICE.

No. 848,818.

Specification of Letters Patent.

Patented April 2, 1907.

Application filed August 1, 1906. Serial No. 328,800.

To all whom it may concern:

Be it known that I, CHARLES H. FORT, a citizen of the United States, residing at Stafford, in the county of Stafford and State of 5 Kansas, have invented a new and useful Measuring Device, of which the following is a specification.

This invention relates to devices for measuring fabrics; and its object is to provide a 10 combined holder and measuring device which is particularly adapted for supporting and measuring heavy fabrics—such as oil-cloth, wire-netting, &c.—which are placed upon the market in rolls.

15 Another object is to provide a device of this character which is of compact construction and which has a foldable table on which the fabric may be placed while being measured.

20 A still further object is to provide a straight-edge or guide whereby a straight cut may be made in the fabric at the point where the same is to be severed.

With the above and other objects in view 25 the invention consists of a rack made up of standards supporting a plurality of inclined shelves each of which is adapted to receive one or more rolls of fabric. A trough is disposed upon the rack at a desired point and 30 is located at the inner end of a table which is constructed to fold out of the way when not in use. A straight-edge is movably connected to the rack and is adapted to bear thereon adjacent the trough, and a scale is 35 located upon the table to facilitate the measuring of the fabric.

The invention also consists of certain novel features of construction and combination of parts, which will hereinafter be fully described, and pointed out in the claims.

In the accompanying drawings is shown the preferred form of the invention.

In said drawings, Figure 1 is a side elevation showing in dotted lines the positions of the parts when raised, one end of the trough being broken away. Fig. 2 is a front elevation of the device. Fig. 3 is a plan view, some of the shelves being broken away to show one end of the trough; and Fig. 4 is a 50 detail view of the trough and straight-edge detached.

Referring to the figures by numerals of reference, 1 1 are bases on which are supported standards 2, said standards being connected adjacent their ends by means of cross-braces 3. Brackets 4 extend in opposite di-

rections from the standards, and their upper edges are inclined and support shelves 5, each of which is adapted to hold one or more rolls of fabric. Arms 6 extend from the 60 standards at points between the ends thereof and are suitably braced by uprights 7. Arranged on these arms close to the standards 2 is a trough 8, the ends of which are closed, as shown, and a cross-strip 9 is mounted on 65 supports 10 and extends along the rear edge of the trough and constitutes a base on which a plurality of L-bolts 11 are disposed. These bolts engage arms 12, which extend from a straight-edge 13, extending the full 70 width of the device. This straight-edge normally rests by gravity close to the front edge of the trough and upon a bed 14, which is suitably protected, as by means of sheet metal, so as to prevent mutilation when a 75 fabric is being cut by an implement drawn thereover. The straight-edge 13 is preferably constructed of brass or other metal which will not be easily injured by a cutting implement.

80 A table-section 15 is connected to the front edge of the trough by means of hinges 16, and it preferably consists of side strips 17, cross-strips 18, and slats 19. Another table-section 20, which is similarly constructed, is hinged to the front edge of the section 15, and both sections are provided along their side edges with scales 21, the 85 graduations of which are consecutively numbered away from the trough 8. A supporting-strip 22 connects the forward ends of the arms 6 and serves to hold the table extended and in an inclined position when the same is in use. When the table is not in use, the section 20 is adapted to be folded onto the section 15 and the entire table then swung up on its hinges 16, so as to be out of the way.

95 As heretofore stated, each of the shelves 5 is adapted to hold one or more rolls of oil-cloth or other material. When it is desired 100 to cut off a predetermined quantity of material from one of the rolls, the table is swung downward, so that the section 15 will rest on the strip 22, and the outer section 20 is then 105 swung outward, so as to form a continuation of the section 15. The roll from which the material is to be cut is then removed from its shelf and placed in the trough 8, the straight-edge 13 and its arms 12 having first been swung into an upright position. After the 110 roll has been placed in this manner the same is partly unwound and drawn over the table un-

til the desired length to be severed has been designated by the scales 21. The straight-edge 13 is then swung downward onto the unwound portion of the roll and will aline with the first 5 graduation of each scale. A knife or other cutting-tool is then drawn along the straight-edge and will cut off the fabric. A straight cut is thus insured, and the proper length of material is severed. After the roll has been

- 10 cut in this manner it can be removed from the trough and replaced on its proper shelf, and if no other rolls are to be cut the table can be folded, as hereinbefore described.

15 In the foregoing description I have shown the preferred form of the invention; but I do not limit myself thereto, as I am aware that modifications may be made therein without departing from the spirit or sacrificing any advantages thereof, and I therefore reserve 20 the right to make such changes as clearly fall within the scope of the claims.

What is claimed is—

1. In a device of the character described, the combination with a roll-holding device 25 and a support therefor, of a foldable table pivotally connected to said device, and a scale upon the table.

2. In a device of the character described, the combination with a roll-holding device 30 and a support therefor, of a foldable table pivotally connected to said device, a scale upon the table, and a straight-edge movably connected to and normally disposed upon the holding device.

35 3. In a device of the character described, the combination with a trough and a support therefor, of a table pivotally connected to the trough, and a scale upon the table.

40 4. In a device of the character described, the combination with a trough and a support therefor, of a table pivotally connected to the trough, a scale upon the table, and a straight-edge movably connected to and normally resting upon the trough adjacent the table.

45 5. In a device of the character described, the combination with a holding-trough and a support therefor, of a sectional table pivot-

ally connected to the trough, a straight-edge normally resting upon the trough adjacent the table, and arms extending from the 50 straight-edge and pivotally connected to the support.

6. In a device of the character described, the combination with a rack, of a holding-trough supported thereby, and a foldable table pivotally connected to the trough. 55

7. In a device of the character described, the combination with a rack and a trough supported thereby, of a sectional table pivotally connected to the trough, and means 60 for supporting the table in extended position.

8. In a device of the character described, the combination with a rack and a trough supported thereby, of a sectional table pivotally connected to the trough, means for 65 supporting the table in extended position, and a scale upon the table.

9. In a device of the character described, the combination with a rack and a trough supported thereby, of a sectional table pivotally connected to the trough, means for 70 supporting the table in extended position, a scale upon the table, a straight-edge normally resting upon the trough adjacent the table, and arms extending therefrom and 75 pivotally connected to the rack.

10. In a device of the character described, the combination with supporting-standards and inclined shelves carried thereby; of a trough supported by the standards, a foldable table pivotally connected to and adapted to fold over the trough, means connected to the standards for supporting the table in extended position, and a straight-edge movably connected to the standards and normally bearing upon the trough adjacent the table. 85

In testimony that I claim the foregoing as my own I have hereto affixed my signature in the presence of two witnesses.

CHARLES H. FORT.
